MINERAL OIL SOLUTIONS

Eric C. Kunz, Montclair, and Alphonse T. Fiore,
Passaic, N. J., assignors to Givaudan-Dela-
wanna, Inc., New York, N. Y., a corporation
of New York

No Drawing. Application March 26, 1938,
Serial No. 198,228

7 Claims. (Cl. 167—24)

This invention relates to mineral oil solutions and has for its object to provide new and improved solutions of mineral oil distillates and other materials which are normally insoluble or only slightly soluble therein.

Another important object of the invention is to provide an improved liquid insecticide comprising a mineral oil distillate, rotenone or rotenone extract, and a material which substantially increases the normal solubility of the rotenone in the mineral oil distillate.

Mineral oil distillates have special properties which make them desirable as carriers or solvents for liquid sprays, particularly for insecticides, paint sprays, perfume sprays, pharmaceutical products, etc.; but certain organic substances, which would otherwise be highly effective as the active ingredients of such sprays, have heretofore not been used because they are insoluble or only slightly soluble in such mineral oil distillates. Among such organic substances may be mentioned rotenone, oleoresins containing rotenone, vanillin, coumarin, dibenzylidene acetone, rosin, olibanum oleoresin, etc.

We have now discovered that alkyl phenols of the general formula:

and mixtures of such phenols have an unexpected solvent effect for maintaining in mineral oil distillates the above-mentioned organic substances which are soluble in alkyl phenols but are otherwise insoluble or only slightly soluble in the mineral oil itself. R and R_1 in the above formula are alkyl groups while R_2 may be hydrogen or an alkyl group so that the total number of carbon atoms in the alkyl groups is not less than 3 and does not exceed 16.

We have also found that these alkyl phenols increase the compatibility of other phenolic and non-phenolic materials which when used alone are not satisfactory as solvents for rotenone and allied products in mineral oil distillates. As examples of such materials may be mentioned:

Oleic acid
Camphor
Dimethyl aniline
Nitrophenols
Aliphatic ketones
Pine oil
Aryl phenols
Chlor alkyl phenols and cresols
Camphor oil, etc.

As specific examples of alkyl phenols according to the above formula may be mentioned:

Mono and di isopropyl phenols and cresols, such as thymol and carvacrol, and mono isopropyl xylenols.

Butyl and isobutyl cresols and xylenols.

Amyl and isoamyl cresols and xylenols.

Dibutyl and di isobutyl phenols and cresols.

Diamyl and di isoamyl phenols and cresols.

Diethyl phenol.

Natural products containing such phenols as for instance, oil thyme, origanum, etc.

It is to be noted, however, that the various alkyl phenols differ in their efficiency for maintaining rotenone and other substances in solution. For instance, .5% of mono or di-iso propyl cresol will maintain .05% rotenone in a 40 Saybolt viscosity mineral oil whereas 1% of cresols or xylenols are necessary to obtain the same effect. For maintaining in mineral oil solution such products as rotenone and the other active principles found in Derris, cube, etc. the greatest efficiency is exhibited by alkyl phenols in which the total number of carbon atoms in the alkyl groups varied between 3 and 8. Likewise a change in the viscosity of the mineral oil as well as a change in the rotenone concentration will necessarily affect the concentration of the solvent required to maintain a given concentration of rotenone in solution.

For instance, $\frac{1}{2}$ of 1% of iso propyl xylenol will maintain .05% rotenone in a 40 Saybolt viscosity mineral oil while only 3% of iso propyl xylenol is necessary to maintain .5% rotenone solution in the same mineral oil; or expressed otherwise, 10 parts of alkyl phenols and 1 part of rotenone or rotenone oleoresins will maintain the rotenone in mineral oil solution in all concentrations above .05% while a ratio of only 6 parts of alkyl phenol to 1 part of rotenone is required for mineral oil solutions containing more than $\frac{1}{2}$ % of rotenone.

In cases where the phenolic derivative is solid and has a marked tendency to crystallize from mineral oil solutions, this can readily be overcome by mixing therewith other phenolic or non-phenolic substances so as to obtain a liquid or low melting solution which does not crystallize from mineral oil.

Para tertiary amyl phenol or high melting isomers of thymol or carvacrol when used alone tend to crystallize from mineral oil. However, by mixing these with such phenols as thymol, carvacrol or other liquid phenols a satisfactory

solution results. In the above proportions the alkyl phenol or alkyl phenol mixture can be replaced to the extent of 5-40% by materials listed above such as pine oil, oleic acid, camphor oil, dimethyl aniline, etc.

The above facts are of utmost importance in the production of rotenone sprays for use as insecticides. For the manufacture of a satisfactory oil spray for instance, according to the time 10 of the year, the insect which is to be killed, the nature of the plant to be protected, it is absolutely necessary that the volatility of the solvent and the concentration of the rotenone be properly adjusted, and this can best be accomplished by 15 using a mixture of mineral oils and selecting the proper alkyl phenol or mixtures thereof. All these factors can be adjusted to the utmost nicely through the use of the present invention, it being possible to regulate the volatility of the 20 various ingredients within a wide range. Of course, it goes without saying that other inert or active products may be mixed with rotenone, that other oils or diluents may be mixed with the mineral oil, and that a suitable emulsifier may be 25 added to the mineral oil solution so as to make water sprays from the compounds.

The terms "mineral oil" and "mineral oil distillate" as used herein are meant to include those petroleum distillates or their hydrogenation 30 products which are suitable for use in plant or animal sprays of an insecticidal nature, including products of similar nature obtained in the distillation of products of coal liquefaction or coal hydrogenation. All these products are distillates in which most of the constituents harmful 35 to plants and animals such as nitrogen compounds, sulfur compounds, unsaturated hydrocarbons, pitches, tars and residues, have been removed. The distillates best suited to this purpose are the kerosene and mineral oil fractions or mixtures of both and also their hydrogenated products which have a high unsulfonated residue indicating a high percentage of saturated hydrocarbons. The suitable mineral oil fraction will have a Saybolt viscosity of 40-120.

These distillates all have a slight solubility for rotenone. At room temperature a deodorized kerosene of a specific gravity at 25° of .776 will dissolve .01% rotenone. A mineral oil of 60 Saybolt viscosity will dissolve .023% rotenone. We have made the unforeseen discovery that phenolic compounds, when added in small quantities to kerosene or mineral oil or to mixtures of both, appreciably increase the solvent power for rotenone. Using a mixture consisting of 50% each of kerosene and a white mineral oil Saybolt viscosity 60, the solubility of rotenone will be influenced as follows by the addition of phenolic products.

60

65

Kerosene mineral oil mixture	Phenolic com- pound	Rotenone solubility
Parts	Parts	Percent
99.5	.5	.05
99.0	1.0	.1
98.0	2.0	.3
97.0	3.0	.5

In the prior art attempts have been made to 70 keep rotenone in kerosene solution through addition of chloroform, ether, acetone, benzol, camphor oil, pine oil, etc. All these products are practically worthless when used with mineral oil solutions as concentrations of 3-6% will often be required in order to keep .05% rotenone in so-

lution. Plant sprays containing such large quantities of solvents will be harmful to the plants, as a rule causing undesirable secondary effects like "burning" of leaves.

With the phenolic compounds used according 5 to the present invention, as little as $\frac{1}{2}\%$ will be required for a stable plant spray containing .05% rotenone and therein lies the decided advantage over all other known solvents. The phenolic compounds have the further very desirable quality of low volatility insuring their remaining in the mineral oil or kerosene after spraying, thereby keeping the rotenone in solution, or in other words in molecular dispersion which is the state of highest insecticidal activity. 15 The volatility of the phenolic compounds useful within the scope of this invention on the other hand is of an order greater than that of mineral oil, which quality will avoid the formation of harmful concentrations after spraying. 20

In preparing insecticidal solutions containing mineral oil or kerosene or both, together with rotenone and the other toxic insecticidal substances contained in the oleoresin of Derris, cube, timbo, etc., we prefer to first dissolve the rotenone 25 or rotenone containing oleoresin in the alkyl phenol or mixture of these phenols, making a solution of 1 part by weight of rotenone and 5-10 parts by weight of the phenol or phenol mixture. This concentrated solution can then be 30 diluted with mineral oil or kerosene or both to yield finished insecticidal sprays containing from .05 to .5% rotenone or oleoresins containing rotenone. If necessary for special purposes solutions of concentrations which are higher than 35 .5% rotenone can be obtained by addition of less mineral oil. Such solutions are useful for emulsification with water or other emulsified sprays.

Our rotenone solutions in mineral oil are mixable with pyrethrum extracts and organic thiocyanates and iso thiocyanates and are therefore 40 very useful to strengthen these other insecticidal solutions.

Isopropyl m-p-cresol mixture	32
Oleoresin derris or cube	10
Rotenone	2.5
Mineral oil	24.5

In connection with the foregoing methods and compositions, we might mention that it is easier to dissolve rotenone than to dissolve the oleoresin containing rotenone as obtained in the extraction of Derris, cube, timbo root, etc., with solvents. The composition of the oleoresin depends to some extent on the organic solvent used for the extraction. By using our invention it is possible to employ Derris, cube, etc., oleo-

resin manufactured with any of the commonly used solvents as the phenolic compounds have the very great advantage of selectively dissolving only the insecticidally active ingredients of the oleoresin. The undesirable material can easily be eliminated by filtration of the solution of the oleoresin in the phenolic compounds. This represents a very simple way of refining the oleoresin which is of great practical value.

10 It will be evident to those skilled in the art that various changes may be made in the foregoing compositions and methods of manufacture without departing from the scope and spirit of the invention as defined in the appended claims.

The invention claimed is:

1. A liquid insecticide comprising a solution of the following materials in substantially the following proportions by weight: mineral oil distillate 96.5%, iso propyl cresols 2.25%, pine oil 0.75%, and rotenone or an oleoresin containing rotenone 0.5%.

2. Insecticidal compositions containing mineral oil distillate, an alkyl substituted cresol selected from the class consisting of butyl and iso-butyl cresols, and a third substance selected from the group consisting of rotenone, oleoresins containing rotenone, and the insecticidally-active principles of Derris, cube and timbo, said third substance being present in said composition 30 in an amount greater than its normal solubility in said mineral oil alone.

3. An insecticidal composition containing mineral oil distillate, an alkyl phenol selected from the group consisting of thymol and its isomers, and a third substance selected from the group consisting of rotenone, oleoresins containing rotenone, and the insecticidally-active principles of Derris, cube and timbo, said third substance being present in said composition in an amount 40 greater than its normal solubility in said mineral oil alone.

4. An insecticidal composition containing mineral oil distillate, a poly-alkyl phenol of the general formula

50 wherein R and R₁ are alkyl groups and R₂ is H or alkyl, the total number of carbon atoms in the alkyl groups being not less than 3 and not more than 16, each alkyl group containing not more than 8 carbon atoms therein, and a third substance selected from the group consisting of

rotenone, oleoresins containing rotenone, and the insecticidally-active principles of Derris, cube and timbo, said third substance being present in said composition in an amount greater than its normal solubility in said mineral oil alone.

5. An insecticidal composition containing mineral oil distillate, a poly-alkyl phenol of the general formula

15 wherein R and R₁ are alkyl groups and R₂ is H or alkyl, the total number of carbon atoms in the alkyl groups being not less than 3 and not more than 16, each alkyl group containing not more than 8 carbon atoms therein, and at least 0.05% of a third substance selected from the group consisting of rotenone, oleoresins containing rotenone, and insecticidally-active principles of Derris, cube and timbo.

6. An insecticidal composition containing mineral oil distillate, a poly-alkyl phenol of the general formula

20 wherein R and R₁ are alkyl groups and R₂ is H or alkyl, the total number of carbon atoms in the alkyl groups being not less than 3 and not more than 16, each alkyl group containing not more than 8 carbon atoms therein, and a rotenone-containing substance, said rotenone-containing substance being present in said composition in an amount greater than its normal solubility in 35 said mineral oil alone.

7. An insecticidal composition containing mineral oil distillate, a poly-alkyl phenol of the general formula

40 wherein R and R₁ are alkyl groups and R₂ is H or alkyl, the total number of carbon atoms in the alkyl groups being not less than 3 and not more than 16, each alkyl group containing not more than 8 carbon atoms therein, and 0.05%-0.5% of a rotenone containing substance.
